UNITED STATES PATENT OFFICE.

CORNELIUS S. CLARK, OF NORFOLK, VIRGINIA.

NUT-LOCK.

No. 853,062.

Specification of Letters Patent.

Patented May 7, 1907.

Application filed September 11, 1906. Serial No. 334,158.

To all whom it may concern:

Be it known that I, CORNELIUS S. CLARK, a citizen of the United States, residing at Norfolk, in the county of Norfolk and State of Virginia, have invented new and useful Improvements in Nut-Locks, of which the following is a specification.

This invention relates to nut locks and the object of the invention is to provide a nut lock in the manner as hereinafter set forth which will lock the nut upon the bolt and prevent the nut from working loose or becoming detached.

The invention further aims to provide a nut lock in the manner as hereinafter set forth which shall be simple in its construction, strong, durable, efficient in its use, readily set up and comparatively inexpensive to manufacture.

With the foregoing objects in view the invention consists of the novel construction, the combination and arrangement of parts hereinafter more specifically described and illustrated in the accompanying drawings wherein is shown a preferred embodiment of the invention, but it is to be understood that changes, variations and modifications can be resorted to which come within the scope of the claims hereunto appended.

In describing the invention in detail reference is had to the accompanying drawings wherein like reference characters denote the corresponding parts throughout the several views and in which—

Figure 1 is a side elevation of a nut lock in accordance with this invention showing the same in a locking position. Figs. 2 and 2^a are, respectively, a side and rear view of the nut. Figs. 3 and 3^a are like views of the locking washer, and Fig. 4 is a side elevation or modified form of nut lock.

Referring to the drawings by reference characters 1 designates a bolt of ordinary construction, on the threaded end 2 of which is applied a nut and a washer in accordance with this invention. The nut is indicated by the reference character 3 and has its inner face provided with a cylindrical boss 4, the periphery of which is uninterrupted and the said boss 4 is surrounded by a smooth and uninterrupted marginal portion 5 on the inner face of the nut 2. When the nut 3 is screwed home the boss 4 bears against one face of the object 6 to be clamped or locked in position so that between the object 6 and the marginal portion 5 which surrounds the

boss 4 a recess is formed and in the said recess is positioned the locking washer 7. The locking washer 7 consists of a flat ring having on one face thereof a pair of piercing barbs 8 which are arranged opposite each other, and the said washer 7 has upon its opposite face a pair of piercing barbs 9 which are arranged opposite each other, but the pair of piercing barbs 9 are arranged at right angles with respect to the pair of piercing barbs 8. Each of the barbs 8 and 9 do not extend entirely across the washer 7, and when the washer 7 is in position, which is when surrounding the boss 4, and when the nut 3 is screwed home the barbs 9 bite the object 6, and the barbs 8 bite in the marginal portion 5, consequently locking the nut to the sub-structure for the reason that the washer 7 is locked to the object 6. When the nut 3 is screwed home the washer assumes the position shown in Fig. 1, that is to say, it is bent in a torsional manner.

In the construction shown in Fig. 4 the bolt is indicated by the reference character 10, and the head of the bolt is formed with a boss 11 surrounded by a smooth marginal portion 12. In this construction the bolt carries a locking washer 13 as well as the nut. The nut is indicated by the reference character 14, its boss by the reference character 15 and its locking washer by the reference character 16. Each of the locking washers 13 and 16 are provided with two pairs of piercing barbs, one pair being indicated by the reference character 17, and the other pair by the reference character 18. By such an arrangement a double lock is provided, the bolt being prevented from movement owing to the biting of the barbs of the washer 13, and the nut is prevented from movement owing to the biting of the barbs of the washer 16.

In use, as is clearly shown in Fig. 1, it will be observed that the boss will have a direct bearing against the face of the fish-plate or other object, thus sustaining the strain, while the washer has a slight yielding action between the fish-plate and nut, and the barbs enter the fish-plate or nut so as to prevent the nut from turning or working loose, and the same is true in connection with the bolt. However, when it is desired to remove the nut from the bolt, the washer will yield sufficiently for this purpose at the two sides carrying the engaging portion to allow the nut to be turned backward so that the barbs will be moved from biting engagement with either

the fish-plate or the marginal portion of the nut or bolt.

By the construction of nut and washer herein shown and described it will be seen that the inner end of the nut may be brought to bear directly against the fish-plate or other object to which the bolt is applied, thus enabling the parts to be firmly secured, the same being sustained entirely by the nut, while the yieldable washer prevents the nut from turning backward or working loose, and the same is true when the bolt is provided with the locking washer for the reason that the boss of the bolt can bear against the fish-plate as well as the boss of the nut. When the double lock is used the strain is had upon the nut and boss of the bolt.

What I claim is—

1. A nut lock comprising a nut having one face thereof provided with a boss having a smooth and uninterrupted periphery, said boss surrounded by a smooth and uninterrupted marginal portion, and a flat, yieldable and circular washer mounted upon said boss and provided on each face with a pair of piercing barbs, the barbs upon one face arranged at an angle with respect to the barbs upon the other face, said barbs arranged upon the inner marginal portion of said washer and of a length less than the width of the body portion of the washer.

2. A nut lock comprising a nut having one face thereof provided with a boss having a smooth and uninterrupted periphery, said boss surrounded by a smooth and uninterrupted marginal portion, and a flat yieldable and circular washer, mounted upon said boss and provided on each face with a pair of piercing barbs, the barbs upon one face arranged at an angle with respect to the barbs upon the other face, combined with a bolt provided with a screw-threaded portion adapted to receive said nut and further having the head formed with a boss surrounded by a smooth marginal portion; and a yieldable washer mounted upon the boss of the nut, said washer having each of its faces provided with a pair of piercing barbs, the barbs upon one face positioned at an angle with respect to the barbs of the other face, the barbs formed on the washer carried by the bolt arranged upon the inner marginal portion of said washer and of a length less than the width of the body portion of the washer.

In testimony whereof I have hereunto set my hand in presence of two subscribing witnesses.

CORNELIUS S. CLARK.
